UNITED STATES PATENT OFFICE

ALLAN C. HODGE, OF BURBANK, CALIFORNIA

FIREARM CUSHION

Application filed February 26, 1929. Serial No. 342,927.

This invention relates to an improved cushion for the butt end of fire arms of different types adapted to function as a shock absorber and located to permit it to be placed comfortably against the shoulder when firing.

More specifically stated, the invention has reference to an attachment in the form of a cap or sleeve which is intended to fit telescopically over the butt end of the stock, wherein the same embodies an integral pneumatic pad or cushion.

My principal object is to provide a simple and inexpensive article of this class which is easy to apply and remove and which is unusually successful and efficient in use.

In the drawings:

Figure 1 is a fragmentary side elevational view of a fire arm equipped with the improved cushion attachment.

Figure 2 is a sectional view through the attachment, showing the approximate position on the stocks.

Figure 3 is an end view of the attachment looking in the direction from left to right.

Figure 4 is a horizontal sectional view through the central portion of the attachment.

In carrying out the invention, I provide a Pará rubber body generally designated by the reference character 5.

It is formed to provide a tapered elastic retaining sleeve 6, which fits telescopically over the butt end of the stock 7 of the fire arm 8. As shown in Figure 2 it is provided with an internal diaphragm or partition 9, cooperating with the adjacent end 10 in forming a pneumatic chamber 11. The features 9, 10 and 11, form an air cushion or pad adapted to be placed against the shoulder of the user to absorb shock.

As seen in Figure 2 of the drawing, the partition 9 and end wall 10 are thickened at their opposed marginal portions where the greatest strain occurs due to the recoil of the fire arm. The thickened marginal portion of the partition 9 receives the thrust from the gun when the same is fired, thus preventing said partition from being torn from the sleeve 6.

The air is inserted by means of a needle and upon withdrawing the needle the opening formed thereby automatically closes in an obvious manner.

Attention is called to the omission of valves and other extraneous elements usually employed in connection with inflation tabs and the like.

The attachment is applicable to various species and forms of fire arms and is especially suitable for fulfilling the requirements of an invention of this class in an unusually satisfactory manner. It is thought that, however, these and other features and advantages of the invention have doubtless been made apparent from the description and drawings. Therefore a more lengthy description is regarded as unnecessary.

Minor changes in shape, size and rearrangement of details coming within the field of invention claimed may be resorted to, in actual practice, if desired.

I claim:

As a new product of manufacture, an attachment for fire arms comprising a single body of rubber including a tapered retaining sleeve having an end wall and an internal transverse partition spaced from said end wall and forming an air chamber, the opposed marginal portion of the partition and end wall being thickened in a manner to reinforce the same.

In testimony whereof I affix my signature.
